AUTOMATICALLY PRIMED SIPHON MECHANISM FOR FLUSHBOXES

Marcel Nestor Jules Delvoye, Verviers, Belgium

Application February 25, 1954, Serial No. 412,519

Claims priority, application Belgium March 3, 1953

4 Claims. (Cl. 137—135)

This invention relates to flushboxes and more especially to the kind of apparatus which is fitted for automatic periodical priming so as to effect at predetermined intervals a flushing of pipe systems, for instance for the flushing of containers or the mixing or measuring of liquids of different kinds.

In the drawings affixed to this specification and forming part thereof an embodiment of the invention is shown diagrammatically by way of example.

In the drawings:

Fig. 1 is a perspective view of the apparatus with part of the front wall cut away.

Fig. 2 is a vertical section, and

Figs. 3 to 7 are similar views illustrating various details of construction.

Referring to the drawings, 1 is a flushbox, 2 is its cover, 3 is a filling pipe in the cover and 4 is the flush pipe.

According to this invention, there is provided within the box 1 a siphon tube 5 of U-shape which in this embodiment is a flat pipe ending in a funnel 6 and carries a stop member 7. The siphon tube 5 is pivoted at 8¹ (Figs. 2 and 3) to a connecting pipe 8 which is mounted on the bottom plate of the box and into which the siphon tube 5 discharges. The entering cross-section of the pipe 8 is equal to its exhaust section and forms a connection 9 between the siphon tube 5 and the flush pipe 4.

The pivot connection between the siphon 5 and the pipe 8 is tightly sealed by a membrane 10 of flexible waterproof material which is fixed to the top part of the pipe 8 and pressed against, and fixed to, a plate 11 at the end of the siphon pipe 5. 12 is a counterweight fixed to this plate.

A characteristic feature of this device is the float body 14 mounted by means of pivot pins 13 on the intake end of the siphon tube. The lifting power of this body is greater than the force exerted by the weight of the siphon on the pins 13. The form and location of these pins is so chosen that the float, when empty, floats on the liquid. When filled and surrounded by air, the float is in a state of unstable equilibrium causing it to pivot on the pins 13.

The air-filled float proper 15 extending longitudinally of one side of the open float surface serves for keeping this surface above the level of the liquid when the body 14 is immersed. If necessary, more than one float may be arranged around the intake pipe of the siphon. A check 15' extending over the entire width of the box 1 limits the lifting movement of the device and determines the highest liquid level.

This device operates as follows.

The box 1 is filled by a predetermined quantity of liquid streaming in which can move in as rapidly or slowly as desired, even in a drop by drop manner. While the box is empty, the different parts occupy the positions shown in Fig. 4. When the liquid level rises in the box, the float 15 is lifted and rocks the float body 14 which then assumes the position shown in Fig. 5. From that point on the lifting power of the body 14, which remains empty,

suffices for lifting the tube 5 and its pivots on the member 8 on the exhaust side. While the liquid level rises further, the body 14 meets the check 15' which arrests it (Fig. 6). However, since the liquid level continues rising, the liquid issuing from 3 flushes the body 14 and removes its carrying power. Under the weight of the liquid which fills the body 14, the combined siphon 5 and body 14 are forced to submerge in the liquid and the box is now filled completely.

10 The siphon immersed in the liquid now primes itself irremediably (Fig. 7) and the liquid in the box flows, as shown by the arrows, toward the discharge pipe 4 so that the box is rapidly emptied. The body 14, which, when full, is in a state of unstable equilibrium when surrounded by air, is emptied also entirely and rocks back into the position shown in Fig. 4. The apparatus has now returned to its initial position, and since new liquid streams in continually, a new period of action begins automatically.

20 It is the fixed check 15' which determines exactly the liquid level in the box 1.

Means may be provided for interrupting the functioning of the apparatus, for instance in the form of an arm 16 (Figs. 1 and 2) which can pivot on a shaft 17 mounted on a support 18 fixed on the cover 2 and carrying a hook 19 which extends into the interior of the box 1 and can engage a ring 20 on the tube 5. It is therefore easy to maintain the siphon in the elevated position where it serves as an overflow. In order to return the apparatus 30 into working position, all that is needed is to disengage the hook 19 from the ring 20.

The new device distinguishes over similar devices hitherto known by being of simple design and still offering entire security of working. It is not exposed to getting 35 dirty or to be worn out soon and does not present a mobile joint. It does not require attendance and functions precisely at any filling speed. It is fit to be used for all purposes and for smallest and greatest outputs.

By simply hanging up the siphon in its top position, 40 it will serve as overflow until it is set free again and starts again working automatically. No priming by hand is required to start it functioning, no liquid seal is provided and its operation may be discontinued for any desired period of time. As soon as it is filled again, it will resume 45 its automatic cycle of operations.

The two pivot members on the siphon tube and on the float, respectively, are not subject to excessive wear nor do they have any detrimental influence on the operation of the apparatus, because (1) the movement executed by 50 the pivots is negligible, and (2) any play of the pivots would not in any way influence the operation.

Liquids charged with solid matter may be handled by the device as easily as pure liquids without any danger of deposits forming so as to disturb the operation, be- 55 cause there is no conduit present excepting the siphon.

No failure can occur as long as the box is not damaged. If it should be damaged, the liquid level in the box can- 60 not rise above the siphon which acts as an overflow, and the box can easily be emptied altogether by hanging up the siphon in top position until it is filled. After disen- gagement the siphon will at once start working again.

The ring which serves for hooking up the siphon, re- 65 mains always free of the liquid and the release level always remains constant.

If it is desired to be able to throw the apparatus in and out by remote control, an electromagnet can be used which is set operating by means of a push-button, to set off as many flushings as required. With the aid of a 70 clockwork mechanism the device can be timed at will.

If no electric current is available, a simple clockwork set for any predetermined moment can be used.

Any standard installation can be provided with the de-

device, and no particular precision of working is required. The device can be fixed in place on the bracket carrying the flush pipe and nothing but the liquid supply tube need be connected.

In order to obtain a thorough emptying of the box, a retaining trap may be provided at the bottom of the box as shown at 21 in Fig. 2.

I wish it to be understood that I do not desire to be limited to the details described in the foregoing specification and illustrated in the drawings, for obvious modifications will occur to a person skilled in the art.

I claim:

1. Automatic liquid dispenser of the kind including a tank continuously supplied with liquid, and a substantially U-shaped siphon pivotally supported in said tank and linked, at one end, to the discharge conduit of the tank, comprising, in combination, a siphon in the form of a flat tube of substantially rectangular section, the free end of said siphon tube being substantially funnel-shaped, a float including a container portion open at the top, and a floatation supporting portion integral with said container portion, pivotally connected with said siphon, a check mounted in the top portion of said tank, said float being adapted to be pivotally displaced, at the start of the tank filling operation, into its floating position and to

pivotsly displace said siphon until, as the liquid level rises, said float abuts against said check whereby said float container portion is filled with liquid, descends in the liquid and by a corresponding lowering of the siphon

5 causes a rapid discharge of the tank.

2. Automatic liquid dispenser according to claim 1 wherein the float container portion has a substantially rectangular side, the floatation supporting portion extending along substantially said entire side.

10 3. Automatic liquid dispenser according to claim 1, wherein the check is a bar extending over substantially the entire length of the float.

4. Automatic liquid dispenser according to claim 1, comprising fastening means provided in the top portion 15 of the tank, and corresponding fastening means provided on the siphon, whereby to arrest the siphon in a fixed position by interengagement of said fastening means.
